UNITED STATES PATENT OFFICE.

WILLIAM M. HOFFMAN, OF BUFFALO, NEW YORK, ASSIGNOR TO HIMSELF
AND EDGAR B. STEVENS, OF SAME PLACE.

PUTTING-OUT MACHINE.

SPECIFICATION forming part of Letters Patent No. 310,279, dated January 6, 1885.

Application filed September 16, 1884. (No model.)

To all whom it may concern:

Be it known that I, WILLIAM M. HOFFMAN, a citizen of the United States, residing in Buffalo, in the county of Erie and State of New York, have invented certain new and useful Improvements in Putting-Out Machines, of which the following is a specification.

The object of my invention is to provide a new and effective means for striking out and putting out the grain, so as to remove the water and other imperfections from calf or other skins.

It is well known that a skin, after being taken from the tanning-vat previous to being fully tanned, is put through a process usually called "striking-out." This process stretches the skin and removes the grain and other imperfections therefrom. The object of this first operation or striking-out is to make the tanning process more rapid, and to stretch the skin to its full length or size. The skin is now returned to the tanning-vat and fully tanned, and then taken out of the vat and put through the first process again. It is then colored, after which, and previous to being hung up to dry, it is put through a process termed "putting-out," which renders the grain side of the skin smooth and removes all imperfections from the flesh side.

The construction and operation of my invention will be fully and clearly hereinafter shown and described, by reference to the accompanying drawings, in which—

Figure 1 is a front elevation; Fig. 2, a plan or top view. Fig. 3 represents a side elevation, taken from the driving-pulley side of the machine; and Fig. 4 is a vertical section through line x x , Fig. 1, the gear-wheels being left off.

The frame a of the machine may be constructed either of cast-iron or wood. a' is the putting-out cylinder. It is provided with the usual spiral blades, a^2 . The putting-out cylinder is usually constructed of wood, and the spiral blades of brass. It is provided with a central shaft, a^3 , of iron or other suitable material, and is journaled in two arms, a^4 , in boxes a^5 . The arms a^4 are secured loosely to the driving-shaft b , which shaft is mounted in boxes b' .

b^2 is the driving-pulley.

On the driving-pulley side of the machine is a gear-wheel, b^3 , keyed or otherwise securely fastened to the shaft b . This gear-wheel b^3 gears into the pinion b^4 on the putting-out-cylinder shaft and gives it the required movement. At the opposite end of the main shaft is a pinion, b^5 , which engages with the spur-wheel c , which is secured to a shaft, c' .

Fitted in bearings c^2 c^3 (see Fig. 2) at the outer end of the shaft c' is a bevel gear-wheel, c^4 , which gears into a bevel gear-wheel, c^5 . The gear-wheel c^5 is rigidly secured to a shaft, d , which shaft is mounted in bearings d^2 d^3 , the bearings being on brackets or supports secured in any well-known way to the side frame. Near the opposite end of the shaft d is a bevel-pinion, d^4 , which gears into a bevel gear-wheel, d^5 . This wheel d^5 is keyed or otherwise secured to the shaft d^6 of the lower feed-roller, e .

e' is the upper feed-roller.

To the arms a^4 is jointed, to each, an arm, e^2 e^3 , by joints e^4 e^5 , having their opposite ends jointed to the treadle f by joints f^2 f^3 . The treadle-levers f^4 are secured to a shaft, f^5 , and each extends backward, so as to receive a counter-weight, f^6 . In front of each of the feeding-rollers is a cleaning-roller or rotary brush, g g' , receiving their movement from the gearing g^2 g^3 g^4 ; but their movements may be given by belts and pulleys arranged in any suitable or well-known way.

In operating the machine the skin is thrown over the upper feed-roller, e' , over which it passes until it is caught in rollers e and e' . A pressure on the foot-step then brings the putting-out cylinder against the skin, which cylinder is made to revolve rapidly, (about six hundred revolutions per minute, while the feed-rollers make about eighteen turns per minute,) and cleans off the small pieces of flesh or other matter adhering to the skin, and stretches the same both ways, taking out the wrinkles or other imperfections, so as to leave it smooth and clear. This operation finishes one-half of the skin, which is then taken out, and the opposite end treated in the same manner, so as to complete it.

The rods or arms $c^2 c^3$ for connecting the foot-step and putting-out-cylinder arms a^4 are provided with a device, h , for readily lengthening and shortening the length of these arms.

5 The object of this arrangement is to provide the means for quickly adjusting their length. For instance, if a stated pressure of the putting-out cylinder is required upon the skin, the length of the arms is adjusted so that when the required pressure is put on the foot-step will touch the floor, so that neither more nor less pressure can be obtained. In this way the exact pressure required may be given to the skin.

15 I claim as my invention—

The combination, in a putting-out machine, of a driving-shaft, b , carrying a gear, b^3 , a putting-out cylinder, a' , supported on a shaft, a^1 , journaled in arms a^4 , pivoted to the shaft b , gear b^4 on the shaft a^5 , engaging with the gear-wheel b^3 , and feed-rollers $e^2 e^3$ below the cylinder a' , and extensible rods $c^2 c^3$, each connected at one end to the arms a^4 , and at the opposite end to the pivoted and counter-weighted foot-treadle f , substantially as and for the purpose described.

WILLIAM M. HOFFMAN.
